UNITED STATES PATENT OFFICE.

SAMUEL M. RIKER, OF CHESTER, NEW JERSEY.

BELT BUCKLE.

Application filed August 15, 1922. Serial No. 581,997.

To all whom it may concern:

Be it known that I, SAMUEL M. RIKER, a citizen of the United States, residing at Chester, in the county of Morris and State 5 of New Jersey, have invented certain new and useful Improvements in Belt Buckles; and I do hereby declare the following to be a full, clear, and exact description of the invention, such as will enable others skilled 10 in the art to which it appertains to make and use the same, reference being had to the accompanying drawings, and to characters of reference marked thereon, which form a part of this specification.

15 This invention has reference, generally, to improvements in belt buckles; and the invention relates to a novel construction of plate buckle having a detachable gripping or clamping means slidably related to the 20 main body thereof, and to which one end of the belt is fixed; said gripping or clamping means being held in gripping relation to the adjustable end of the belt by the longitudinal strain or pull to which the latter is subjected when in operative encircling 25 relation to the waist of the wearer.

The invention has for its principal object to provide a very simple construction of plate belt buckle consisting of a main body 30 and a slidable gripping or clamping element separable from said main body, whereby the adjustable end of the belt may be once adjusted relative to the main body, and thereafter the belt may be taken on and off by 35 merely manipulating the separable gripping or clamping element to attach or detach the same from operative relation to said main body; said gripping or clamping element, when attached to the main body being adapt- 40 ed to automatically slide thereon into operative gripping or clamping relation to the adjustable end of the belt, to securely hold the latter against displacement while around the person of the wearer.

45 Other objects of this invention, not at this time more particularly enumerated, will be clearly understood from the following detailed description of the same.

With the various objects of this invention 50 in view, the same consists, primarily, in the novel construction of belt buckle hereinafter set forth; and the invention consists, furthermore, in the novel arrangements and combinations of the several devices and parts 55 as well as in the details of the construction of the same, all of which will be more fully

described in the following specification, and then finally embodied in the claims appended thereto.

The invention is clearly illustrated in the 60 accompanying drawings, in which:—

Figure 1 is a front face view of the novel buckle with the belt operatively connected therewith; Figure 2 is a similar view with portions of the belt broken away to disclose 65 underlying parts of the buckle structure; Figure 3 is a longitudinal section taken on line 3—3 in said Figure 1; Figure 4 is a transverse section, taken on line 4—4 in Figure 2; Figure 5 is a front face view of 70 the detachable or separable clamping or gripping element of the buckle when separated from the main buckle body; Figure 6 is a perspective view of the main body 75 of the buckle; and Figure 7 is a perspective view of the separable clamping or gripping element of the buckle.

Similar characters of reference are employed in all of the hereinabove described 80 views, to indicate corresponding parts.

Referring now to said drawings, the novel belt buckle comprises a main body consisting of a front or face plate 8, having at its longitudinal edges inwardly projecting side flanges 9. Provided in the body of said 85 face or front plate 8 adjacent to its rearward end is a transverse slot or belt passage 10, and adjacent to its forward end is another transverse slot or belt passage 11. Pressed out of the body of said face or front plate 8, 90 at a point intermediate the slots or belt passages 10 and 11, are a pair of laterally spaced apart inwardly projected guide lugs 12, extending substantially at right angles to the plate of said front or face plate, the free 95 ends of said guide lugs 12 terminating in outwardly extending keeper lugs 13 spaced inwardly from said front or face plate 8, and lying substantially in a plane parallel thereto. Also pressed out of the body of 100 said front or face plate 8, rearward of said guide lugs 12, is an inwardly projected stop lug 14.

The separable gripping or clamping element comprises a clamp-plate 15, the rearward end of which is doubled back upon itself to provide a gripping tongue 16 lying in a plane substantially parallel to the main body of the clamp plate 15 but spaced a short distance therefrom. The forward free 110 end of said gripping tongue 16 is provided with a plurality of gripping serrations 17.

The body of said gripping tongue 16 at point spaced rearwardly from its forward serrated edge is provided with an opening 18. Connected integrally with said gripping tongue 16 at the rearward edge or margin of said opening 18, and so as to extend longitudinally forward from the latter to lie substantially in the plane of said gripping tongue, are a pair of laterally spaced 10 apart coupling fingers 19 adapted at proper times to receive therebetween the guide lugs 12 of the main buckle body. Said coupling fingers 19 terminate short of the forward edge of said opening 18 so as to provide a 15 free transverse space of sufficient area to permit the guide lugs 12 and their keeper lugs 13 to enter through said opening past the free ends of coupling fingers 19. Said coupling fingers 19 are provided at their inner 20 longitudinal or opposed edges with inward projections or humps 20. The coupling fingers 19 and their projections or humps 20, are so spaced apart that the guide lugs 12 at proper times may be entered 25 slidingly therebetween, to spring or snap past said projections or humps 20, said coupling fingers 19 possessing sufficient lateral resiliency to permit of such action, and said projections or humps 20 thus holding 30 the gripping or clamping element against accidental separation from its operative attached relation to the main buckle body. Suitable means are provided in connection with the clamp plate 15 for affixing 35 or attaching thereto one end of a belt 21. Such means may be made in various ways. Illustrative of one form of such attaching means is the transverse loop 22 which extends from the forward end of said clamp plate 15, and to which the fixed end 23 of the belt may be connected in any well known 40 manner.

45 The free or adjustable end 24 of the belt 21 is inserted under the rearward transverse end of the front or face plate 8 to pass outwardly through the rearward slot or belt passage 10 then longitudinally across the outer face of the front or face plate, and thence inwardly through the forward slot or belt passage 11 to issue forwardly from the opposite end of said front or face plate.

In applying the belt to the waist of the wearer, the separable gripping or clamping element is separated from the main body of the buckle, and the belt 21 is arranged about the waist, whereupon the gripping or clamping element and the main body of the buckle are again brought together so that the guide lugs 12 and keeper lugs 13 connected with the front or face plate 8 may be caused to enter through the opening 18 at a point forward of the ends of the coupling fingers 19. A forward longitudinal pull upon the clamp plate 15 will thereupon slide the same forward relative to the main buckle body to

cause the gripping serrations 17 of the gripping tongue 16 to move into gripping engagement with the free end or adjustable portion 24 of the belt 21, to clamp the latter between said serrations 17 and the forward edge of said forward slot or belt passage 11 of the main buckle body. The forward sliding movement of said clamp-plate 15 will cause the coupling fingers 19 to move forward to embrace said guide lugs 12 while the keeper lugs 13 pass over the same to prevent withdrawal or separation of the clamping or gripping element from the main buckle body. This forward sliding movement of the clamping or gripping element relative to the main buckle body also causes the projections or humps 20 of the coupling fingers 19 to spring or snap past the guide lugs 12, in which position they serve to prevent accidental retraction of the clamp-plate 15 and associated parts from operative belt end engaging position. The belt may be adjusted, if necessary, by moving the free end thereof forwardly relative to the main buckle body until the desired tension around the waist is established; under such manipulation the clamp plate 15 being retracted sufficiently to release the serrations 17 of the gripping tongue 16 from operative gripping relation to the belt end. The desired tension thus established, will always operate to pull the clamp plate 15 and associated parts forward so that the bite of the serrations 17 is maintained while the belt is being worn. After an initial adjustment of the belt to the waist of the wearer, it is unnecessary to disturb the adjusted relation established between the free end portion to remove the belt from the wearer's waist, all that is necessary to be done is to push back the clamp plate 15 and associated parts until its rearward end is stopped by the stop-lug 14 of the main buckle body, whereby the clamp plate is positioned so that the guide lugs 12 and keeper lugs 13 have been retracted beyond the free ends of the coupling fingers 17, and thereby alined with the unobstructed open space of the opening 18, so that the main buckle body and clamp plate element may be separated to part the respective ends of the belt. To replace the belt on the wearer's waist the operations thus effected are reversed.

From the above description it will be plain that the novel buckle structure above described is of exceedingly simple construction, comprised of but few parts, and subject to a quick and easy manipulation for the purpose of taking on and off the belt connected therewith from the waist of the wearer. 120 125

I am aware that some changes may be made in the various arrangements and combinations of the devices and parts, as well as in the details of the construction of the 130

same, without departing from the scope of this invention as set forth in the foregoing specification, and as defined in the appended claims. Hence, I do not limit my invention to the exact arrangements and combinations of the various devices and parts as described in said specification, nor do I confine myself to the exact details of the construction of parts as illustrated in the accompanying drawings.

I claim:

1. A belt buckle comprising a face plate transversely slotted adjacent to its respective ends for threading the free end of a belt adjustably therethrough, a pair of laterally spaced guide-lugs inwardly projecting from said face plate intermediate said slots, said guide lugs terminating in keeper lugs spaced in parallel plane from said face plate, a clamp plate having its rearward end doubled back upon itself to provide a forwardly projecting gripping tongue spaced in parallel plane from the main portion of said clamp plate, said gripping tongue having an opening to receive said guide lugs of said face plate, means associated with said opening to engage said guide lugs and keeper lugs to hold said clamp plate operatively attached to face plate, and means for connecting the fixed end of a belt with the forward end of said clamp plate.

2. A belt buckle comprising a face plate transversely slotted adjacent to its respective ends for threading the free end of a belt adjustably therethrough, a pair of laterally spaced guide-lugs inwardly projecting from said face plate intermediate said slots, said guide lugs terminating in keeper lugs spaced in parallel plane from said face plate, a clamp plate having its rearward end doubled back upon itself to provide a forwardly projecting gripping tongue spaced in parallel plane from the main portion of said clamp plate, said gripping tongue having an opening to receive said guide lugs of said face plate, coupling fingers connected with said gripping tongue to project longitudinally forward into said opening so as to embrace said guide lugs upon longitudinal forward movement of said clamp plate, the free transverse edge of said gripping tongue having a plurality of gripping serrations, and means for connecting the fixed end of a belt with the forward end of said clamp plate.

3. A belt buckle comprising a face plate transversely slotted adjacent to its respective ends for threading the free end of a belt adjustably therethrough, a pair of laterally spaced guide-lugs inwardly projecting from said face plate intermediate said slots, said guide lugs terminating in keeper lugs spaced in parallel plane from said face plate, a clamp plate having its rearward end doubled back upon itself to

provide a forwardly projecting gripping tongue spaced in parallel plane from the main portion of said clamp plate, said gripping tongue having an opening to receive said guide lugs of said face plate, coupling fingers connected with said gripping tongue to project longitudinally forward into said opening so as to embrace said guide-lugs upon longitudinal forward movement of said clamp plate, said coupling fingers having at their inner longitudinal edges stop projections to spring past said guide lugs, the free transverse edge of said gripping tongue having a plurality of gripping serrations, and means for connecting the fixed end of a belt with the forward end of said clamp plate.

4. A belt buckle comprising a face plate transversely slotted adjacent to its respective ends for threading the free end of a belt adjustably therethrough, a pair of laterally spaced guide-lugs inwardly projecting from said face plate intermediate said slots, said guide lugs terminating in keeper lugs spaced in parallel plane from said face plate, a clamp plate having its rearward end doubled back upon itself to provide a forwardly projecting gripping tongue spaced in parallel plane from the main portion of said clamp plate, said gripping tongue having an opening to receive said guide lugs of said face plate, coupling fingers connected with said gripping tongue to project longitudinally forward into said opening so as to embrace said guide-lugs upon longitudinal forward movement of said clamp plate, said coupling fingers having at their inner longitudinal edges stop projections to spring past said guide lugs, the free transverse edge of said gripping tongue having a plurality of gripping serrations, and means for connecting the fixed end of a belt with the forward end of said clamp plate.

5. A belt buckle comprising a face plate transversely slotted adjacent to its respective ends for threading the free end of a belt adjustably therethrough, a pair of laterally spaced guide-lugs inwardly projecting from said face plate intermediate said slots, said guide lugs terminating in keeper lugs spaced in parallel plane from said face plate, a clamp plate having its rearward end doubled back upon itself to provide a forwardly projecting gripping tongue spaced in parallel plane from the main portion of said clamp plate, said gripping tongue having an opening to receive said guide lugs of said face plate, means associated with said opening to engage said guide lugs and keeper lugs to hold said clamp plate operatively attached to face plate, and means for

connecting the fixed end of a belt with the forward end of said clamp plate, and a stop post connected with said face plate for determining the rearward limit of movement of said clamp plate relative to said face plate.

In testimony, that I claim the invention

set forth above I have hereunto set my hand this 12th day of August, 1922.

SAMUEL M. RIKER.
